UNITED STATES PATENT OFFICE.

HERMAN STAUB, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING-CARRIER.

1,360,810.

Specification of Letters Patent. Patented Nov. 30, 1920.

Application filed February 25, 1920. Serial No. 361,138.

To all whom it may concern:

Be it known that I, HERMAN STAUB, a citizen of the United States, residing at Wyomissing, in the county of Berks and State of 5 Pennsylvania, have invented certain new and useful Improvements in Braiding-Carriers, of which the following is a specification.

My invention relates to braiding carriers adapted more particularly for single-thread 10 lace-braiding machines and is fully described in connection with the accompanying drawings, the novel features being specifically pointed out in the claims.

Figure 1 is a central longitudinal section 15 of a complete carrier embodying my improvements in preferred form.

Fig. 2 is an enlarged elevation of the tubular extension of the bobbin standard looking at right angles to the Fig. 1 view thereof.

20 Fig. 3 is a plan view of same.

Fig. 4 is a partial longitudinal section of the extension showing the top portion of the spring with cap thereon.

Fig. 5 is a cross-sectional view of same.

25 Fig. 6 is an elevation showing the lower portion of the carrier with the stop sleeve in dropped position thereon.

The type of carrier indicated comprises a base portion 10 guided in the race-way 30 plate 11 of the machine, and having a tubular bobbin standard with a thread-tensioning spring 12 therein arranged to release a bobbin-engaging pawl 13. My invention provides an improved construction and 35 vantageous operation of the carrier as hereinafter fully described.

As shown the base portion 10 is formed with an integral tubular standard portion 15 of circular cross-section; and an upward 40 extension of this standard is provided by a separate tubing having its lower portion 16 snugly inserted in the fixed standard 15. A pawl-supporting bracket 17 rigidly secured to this extension forms a supporting shelf 18 thereon which bears upon the top of the fixed 45 standard 15, and the bobbin 19 inclosing the standard extension rests upon said shelf, with an intervening distance sleeve 20 as required to properly position the pawl-engaging top of any desired length of bobbin. The 50 top of the bobbin standard extension is provided with a thread-guide eye 21, and the thread passes to said eye from the bobbin through guide eyes 22, 23, 24, in the pawl bracket and pawl respectively, engaging a

top eye 25 of the spring 12 so as to be tensioned by the latter.

The upwardly projecting tubing forming the standard extension is made of different cross-section from the cylindrical part thereof of which is engaged in the fixed standard 55 60 15; it being of square cross-section as indicated in Fig. 5 in the portion 30 inclosing the spring 12, with a side wall cut away in the upper portion 31 thereof to provide passage way for the thread, and with the top portion 32 closed upon the porcelain guide eye 21. The spring 12 is provided with a thread cap 35 having a cross-section at 36 conforming with that of the angular standard extension 30, so as to be non-rotatable 65 in the latter though loosely slideable therein. 70

The lower end of the spring 12 is provided with a loop 38, which is engaged by a cross-pin 39 extending through longitudinal slots 40 in the top of the fixed standard 15 and connected to the stop sleeve 41 on the latter; so that said end of the spring will also be held at all times against rotative action, with the sleeve free to drop upon any breaking 75 of the thread. The pawl bracket shelf 18 is formed with a depending offset or offsets 42 engaging the slots 40 so as to positively prevent any turning movement upon the fixed standard.

Important operating advantages result 80 from the positive prevention of spring turning movement which my improved construction provides for. The rapid stretching and contracting of the spring under varying 85 thread tensions I have found to ordinarily produce turning movements of the thread connected end of the spring sufficient to bring the normally approximately parallel 90 portions of the thread into rubbing contact with resulting wear and liability of breakage; and a main purpose and result of my invention is to avoid these effects by positively restricting such turning movement of the thread connected end of the spring as 95 set forth. The improved connection of the lower end of the spring also reduces objectionable wear and tear ordinarily incident to this turning action of the variably tensioned spring. A further practical difficulty 100 largely overcome by my improved construction is clogging of the spring action by accumulation of lint rubbed from the passing thread; the amount of such lint being not 105 only reduced by avoidance of rubbing action, 110

but the spring cap 35 being also adapted to permit the passage of lint close to the wall of the standard extension and practically clear of the spring coil, into the spaces below 5 the spring, from which it may be readily removed at intervals.

What I claim is:—

1. A braiding carrier comprising a base portion having a tubular standard provided 10 with a bobbin-supporting bracket, a spring-guide portion of angular cross-section, and a thread-guide top portion; a thread tensioning spring having a cap of angular cross-section non-rotatably slidable within said 15 spring-guide portion, and a stop sleeve non-rotatably slidable on the standard below said

bracket and connected to the lower end of said spring.

2. In a braiding carrier comprising a base portion having a tubular bobbin standard 20 provided with a thread-guide top portion and a spring-guide portion of angular cross-section; a stop device non-rotatably slidable on the lower portion of said standard and a thread-carried tensioning spring connected 25 at its lower end to said non-rotatable slide stop and having a cap of angular cross-section loosely slidable in said guide-portion of the standard.

In testimony whereof I affix my signature. 30

HERMAN STAUB.
